UNITED STATES PATENT OFFICE.

FREDERICK JOHNSON, OF SOUTH CHICAGO, ILLINOIS.

COMBINED ARCH-PLATE AND SHIELD.

SPECIFICATION forming part of Letters Patent No. 762,417, dated June 14, 1904.

Application filed November 11, 1903. Serial No. 180,658. (No model.)

To all whom it may concern:

Be it known that I, FREDERICK JOHNSON, a citizen of the United States, residing at South Chicago, in the county of Cook and State of Illinois, have invented a new and useful Combined Arch-Plate and Shield, of which the following is a specification.

My invention relates to a combined arch-plate and shield which is employed to support an arch during construction and to protect the mechanics from the extreme heat usually present where it is intended to be used.

My invention is particularly designed to be used in repairing the arches of charging-openings in smelting-furnaces, but may be used for any kind of similar work.

In smelting-furnaces a power-charging mechanism is employed by means of which a large bucket filled with scrap-iron is pushed into the charging-openings and after being emptied inside the furnace is again withdrawn through said opening. While this bucket is being passed through the charging opening, either the bucket or the scrap-iron extending 20 out of the bucket occasionally strikes the edge of the said opening accidentally, and thus seriously mutilates the brickwork forming the contour of the opening. In actual practice it is found that the arches forming the upper side 25 of the charging-openings are most frequently broken. This mutilation must be repaired while the furnaces are in operation to enhance their efficiency. It is necessary to protect the mechanics while repairing the mutilation from 30 the extreme heat within the furnace. Heretofore the mechanic was protected by a temporary brick wall built into the charging-opening, and after the mutilation was repaired the brick wall had to be removed. My invention obviates the necessity of building any 35 temporary protecting-wall whatsoever.

My invention consists of providing a portable protecting-wall composed of any suitable material, as cast-iron, fire-brick, or asbestos, 40 and arranged to fit the charging-openings. The charging-openings in a furnace or set of furnaces are all the same size, so that a protecting-wall made to fit one will fit all. I prefer to provide the protecting-wall with an 45 arch-supporting plate, although this is not

absolutely necessary. I believe I am the first person to construct a portable protecting-wall for smelting-furnaces and lay claim to such a device broadly. I prefer also and have shown in the drawings that the portable protecting-wall be moved into place by the charging mechanism.

It requires several hours by the present mode of repairing these arches to get the protecting-wall into position, while by my invention the same can be accomplished in a few minutes.

It will be understood that radical changes may be made in the form and construction of this device without departing from the spirit 65 of the invention.

I have illustrated in the drawings forming a part of this specification a simple construction of one form of my invention as applied to a smelting-furnace.

Figure 1 is a front elevation of a portion of a furnace, showing several charging-openings. Fig. 2 is a vertical section through one of said openings, showing my invention adapted thereto, and Fig. 3 is a perspective view of the 75 arch-plate and shield.

Similar reference characters refer to similar parts throughout the several views.

The front wall 5 of the furnace is provided with a plurality of charging-openings 6, which 80 are usually rectangular, with an arch 7 forming the top side. In Fig. 1 is shown the ordinary doors 8 to normally close the openings 6 and arranged to be guided in the vertical ways 9. In Fig. 1 one door 8 is shown raised 85 and my improved arch-plate and shield in position, but with the mechanism for holding the same removed.

While I prefer to hold the arch-plate and shield in proper position by the ordinary 90 charging mechanism, I desire to have it understood that any convenient mechanism may be provided for this purpose.

As previously stated, the arches 7 are accidentally broken or partly broken during the 95 regular operations, and these arches must be repaired while the fires are burning within the furnace.

My device consists of the arch-plate 10, which serves to support the brick or similar 100

work in place during construction, and the shield 11, which substantially closes the opening 6 completely.

I prefer having the vertical flange 12 on the 5 inner edge of the arch-plate 10 serve as a stop to rest the arch-bricks against during construction.

Obviously the shield 11 will protect the mechanics on the exterior of the furnace from 10 the extreme heat on the interior of the furnace.

When the device is handled by the ordinary charging mechanism, the front face of the shield 11 is provided with two parallel lugs or 15 ridges 13 and a perforation 14 to fit coöperating parts on the charging mechanism.

In operation when an arch 7 is in need of repair the door 8 is raised out of the way. The arch-plate 10 and shield 11, which are preferably integral, are placed and held in proper 20 position, care being taken to have the outer face of the flange 12 flush with the inner face of the wall 5. The mechanics can now proceed with the necessary repairs without any 25 great inconvenience on account of the heat on the interior of the furnace. As soon as the repairs are complete the device is removed from the opening by the mechanism already referred to.

30 Having thus fully described my invention,

what I claim, and desire to secure by Letters Patent of the United States, is—

1. A combined arch-plate and shield, said arch-plate supporting an arch over a furnace-opening and said shield closing said opening. 35

2. A combined arch-plate and shield, comprising a shield to close the opening in a furnace, an arch-plate to support an arch over said opening and an upward-extending flange on the inner edge of said arch-plate. 40

3. In an arch-plate and shield the combination of a fire-shield to fit into the opening of a furnace, an arch-plate integral with the upper end of said shield to support an arch above said opening, an upward extension on the inner 45 edge of said arch-plate, and two flanges on the outer face of said fire-shield with a hole in the shield between said flanges.

4. A combined arch-plate and shield, said arch-plate arranged to support an arch over a furnace-opening and said shield arranged to fit into said opening. 50

In testimony whereof I have signed my name to this specification, in the presence of two subscribing witnesses, this 2d day of November, 55 1903, at Chicago, Illinois.

FRED. JOHNSON.
